UNITED STATES PATENT OFFICE.

WILLIAM BARTHOLOMEW AND DAVID J. PHILLIPS, OF CHICAGO, ILLINOIS, ASSIGNEES
TO TROY LAUNDRY MACHINERY COMPANY, OF CHICAGO, ILLINOIS, A CORPORATION
OF NEW YORK.

STOPPING DEVICE.

952,407.

Specification of Letters Patent. Patented Mar. 15, 1910.

Application filed August 9, 1909. Serial No. 512,101.

To all whom it may concern:

Be it known that we, WILLIAM BARTHOLOMEW and DAVID J. PHILLIPS, citizens of the United States, residing at Chicago, county of Cook, State of Illinois, have invented certain new and useful Improvements in Stopping Devices, of which the following is a specification, reference being had therein to the accompanying drawing.

10 This invention relates to a stopping device for power driven machinery and particularly to a construction controlled by the movements of an operator in approaching a dangerous moving portion of a machine.

15 The invention has for an object to provide movable safety devices normally held in position to protect the operator and when in such position to retain under tension a power controlling device adapted to be automatically shifted when the safety devices are moved.

20 Another object of the invention is to provide a novel and improved construction of belt shifting mechanism held under tension in driving position by means of a latch connected with a safety device so as to be released in a movement thereof to permit an automatic shifting of a belt to cut off the power from a machine.

25 30 Other and further objects and advantages of the invention will be hereinafter set forth and the novel features thereof defined by the appended claims.

In the drawings—Figure 1 is a front elevation of the invention applied to the frame of a laundry mangle; Fig. 2 is a side elevation thereof with the supporting bracket at the right in section; Fig. 3 is a vertical section through the latch mechanism; Fig. 4 is a section on line 4—4 of Fig. 3; Fig. 5 is a top plan of the latch mechanism; Fig. 6 is a detail elevation of the belt shifter; and Fig. 7 is a side elevation of a modified form of the invention.

45 Like numerals refer to like parts in the several figures of the drawings.

The invention is adapted for application to various types of machines having movable parts by which an operator is liable to be injured when coming in contact therewith. For the purpose of illustration it is herein shown in connection with a laundry mangle in which the numeral 10 designates the frame of the machine upon which the

movable parts are mounted such as the rolls 55 11 with which a feeding apron 12 coöperates, this apron being extended from a feed bracket 13 of usual construction. Adjacent to the feed apron the guard board 14 is suspended by means of the hangers 15 pivoted upon the shaft 16 which may be mounted in any desired support. The free edge 17 of this board has extended from the end thereof an operating rod 18 provided with an angular portion 19 as shown in Fig. 2. 65 This rod is adapted in its inward movement with the board 14 to engage a crank arm 20 carried by a rock shaft 21 mounted in a bearing 22 upon any fixed part for instance a gear casing 23. This rock shaft has 70 at its opposite end an arm 24 connected by a rod 25 with a power controlling device. Coöperating with the board is a cover or screen 26 disposed above moving parts of the machine and secured to a rock shaft 27 75 which is provided at its extended end with a crank arm 28 from which a connector 29 extends to the lever 24. The arm 20 may be provided with a weight 30 or desired tension means to restore it to its initial 80 position.

The parts so far described are adapted to coöperate with any desired power controlling device, and in the modified form of invention shown in Fig. 7 are connected with 85 an automatic switch 31 by which power to an electric driving motor may be cut off. In this form the switch blade 32 is normally held in dotted line position by means of the tension spring 33 and is retained in contact 90 with the switch block 34 by means of a latch lever 35 pivoted at 36 and engaging the switch blade at its end 37. The outer end 38 of this lever is pivoted to the connector 29 controlled by the cover or screen 95 26. Beneath the lever 35 a cam 39 is secured on the rock shaft 21 so that a movement of this shaft caused by either the inward movement of the board or the raising of the cover rocks the lever to release the switch blade 100 and permit its automatic movement to cut off the power.

For the purpose of controlling the power to a belt driven machine a shifting mechanism is used to coöperate with the driving 105 pulleys. These pulleys may comprise the loose pulleys 40 and 41 adapted to receive belts (not shown) which are driven at dif-

ferent speeds in the usual manner. These pulleys are mounted upon a shaft 42 supported in a bearing 43 carried by a bracket 44 for that purpose. Power is transmitted from this shaft in the usual manner to the parts of the machine to be operated. The pulleys 40 and 41 are mounted to freely rotate upon the shaft while the pulley 45 intermediate thereof is fixed to the shaft so as to drive the same. Beneath the shaft 42 is a shifting shaft 46 slidably mounted in a bearing 47 on the bracket and a co-operating bracket 48 adjacent the machine frame. The shaft 46 has secured thereto the opposite guide brackets 49 and 50, one being provided for each belt. These brackets are provided at their lower portion next to latch bolt 57 with inclined faces 52 while the belt guides 53 are secured upon the brackets by means of clamping plates 54. These guides embrace and shift the belt disposed between them.

The latch mechanism comprises a base 55 secured to the bracket 44 in any desired manner and formed with a central tubular casing 56 in which the latch bolt 57 is mounted, the upper end thereof being formed with a curved tooth 58 adapted to seat in a notch or recess 59 formed in the shifting shaft 46 before described. This notch is also formed with an inclined face 60 to facilitate the engagement and disengagement of the bolt tooth therewith. The bolt is formed with a transverse slot or recess 61 within which a cam 62 is disposed and carried by the rock shaft 63 extended therefrom and provided with an operating arm 64. It will be seen that the oscillation of this cam will positively shift the bolt toward and from the shaft 46. This shaft may be held under tension by any desired means in order to restore it to the non-operative position of the machine as shown by full lines in Fig. 1. One form of such a tension device is shown and comprises a chain or cable 65 provided at its lower end with a rod 66 upon which a weight 67 is disposed. This chain extends through the curved tube 68 and is connected to the guide bracket at 69. This tension device is duplicated so as to provide movement in either direction and the tubes therefore have their curved ends oppositely disposed as shown in Figs. 1 and 5.

For the purpose of operating the latch bolt from the safety devices through the rod 25 as shown in Figs. 1 and 2 the arm 64 from the shaft of the cam is connected by a link 70 with one arm of a bell crank lever 71 mounted upon a shaft 72 while the other arm of the lever 71 is pivoted to the rod 25 at 73. When it is desired to operate the belt guides by hand to start or stop the machine an operating handle 74 is disposed upon the shaft 72 and a slotted lever 75 secured to

the shaft to embrace a pin 76 extended laterally from the shifting shaft 46.

In the operation of the invention as applied in Figs. 1 and 2 the belt guides are shown in full lines in position to retain the belts upon the loose pulleys so that the machine is not operated. In order to use either of the two speeds provided the shifting shaft carrying the belt guides is moved by the hand lever either to the right or left as indicated by dotted lines in Fig. 1. Such movement raises one of the weights which exerts a tension to return the shifter to a non-operative position. This return movement is resisted by the latch which engages the shifting shaft and retains the machine in operative position at either speed desired. Under these conditions if the hand of the operator presses against the guard board the rock shaft controlled thereby is shifted and the latch bolt operated through the connections described to permit the weight to automatically restore the belt guides to their initial position. The same action is secured when the cover or screen is raised in order to secure access to the moving parts of a machine.

The starting and stopping of the machine and the application of the different speeds is controlled through the hand lever while the latching bolt automatically seats in the sliding rod through the tension of its connection so that whenever the parts are in driving position they are held under tension and ready to be released by any movement of the board or cover which would endanger the operator. It will therefore be seen that the invention presents a simple and efficient construction by which a machine may be stopped by a slight movement of the safety devices as the application of the tension means does not require any material pressure upon the safety devices to automatically release the tension to effect a shifting of the power.

Having described the invention and set forth its merits what is claimed and desired to be secured by Letters Patent is—

1. The combination with a power controlling device having means under tension for automatically cutting off power, of a rock shaft connected to release said tension means and provided with a lever arm, and a pivoted guard board having means disconnected from said arm and extended from one end thereof to contact with said arm in the movement of the board in one direction.

2. The combination with a power controlling device having means under tension for automatically cutting off power, of a rock shaft connected to release said tension means and provided with a lever arm, and a swinging guard board having means extended from one end of its free edge and disconnected from said arm to engage the latter

- in the movement of the board in one direction.
3. The combination with a power controlling device having means under tension for automatically cutting off power, of a rock shaft connected to release said tension means and provided with a lever arm, and a pivoted guard board provided at one end of its free edge with an extended rod disposed to engage said arm in the inward movement of said board.
4. The combination with a power controlling device having means under tension for automatically cutting off power, of a rock shaft connected to release said tension means, an arm from said rock shaft, and a swinging guard board having means disconnected from said arm to engage and shift it in one movement of said board.
5. The combination with a power controlling device having means under tension for automatically cutting off power, of a rock shaft connected to release said tension means, an arm from said rock shaft, a swinging guard board adapted to engage said arm, a pivoted cover, and a connection from the shaft thereof to said releasing means.
6. The combination with a power controlling device having means under tension for automatically cutting off power, of a rock shaft connected to release said tension means, an arm from said rock shaft, a swinging guard board adapted to engage said arm, a pivoted cover having a crank arm extended from the axis thereof, and a connection therefrom to operate the releasing means.
7. The combination with a power controlling device having means under tension for automatically cutting off power, of a swinging guard board, connections operated thereby for releasing said means when under tension, and a cover member connected to operate said connections independently of said board.
8. The combination with a power controlling device having means under tension for automatically cutting off power, of a swinging guard board, connections operated thereby for releasing said means when under tension, a pivoted cover, and a connection therefrom to the releasing connection.
9. The combination with a power controlling device having means under tension for automatically cutting off power, of a rock shaft connected to release said tension means, a crank arm carried by said rock shaft, and a swinging guard board provided at its free end with an extension to engage said crank arm.
10. The combination with a power controlling device having means under tension for automatically cutting off power, of a rock shaft connected to release said tension means, a crank arm carried by said rock shaft, a swinging guard board provided at its free end with an extension to engage said crank arm, and a weight carried by the free end of said crank arm.
11. In a stopping device, a movable guard member, driving belts, a belt shifter provided with a plurality of holding means, belt pulleys, tension devices connected to said shifter to move it in opposite directions, and means controlled by the guard member for engaging the holding means upon the shifter.
12. In a stopping device, a movable guard member, driving belts, a belt shifter provided with a plurality of holding means, belt pulleys, tension devices connected to said shifter to move it in opposite directions, and a latch mounted to engage either of said holding means and connected to said guard member for operation thereby.
13. In a stopping device, a movable guard member, driving belts, a belt shifter provided with a plurality of holding means, belt pulleys, tension devices connected to said shifter to move it in opposite directions, a sliding latch mounted for movement toward and from the holding means upon said shifter, and connections from the guard member to operate said latch.
14. In a stopping device, a movable guard member, a driving belt, a belt shifter, belt pulleys, a tension device connected to said shifter, a sliding latch mounted for movement toward and from said shifter, a cam mounted to actuate said latch, and a lever arm from said cam connected to said guard member.
15. In a stopping device, a movable guard member, a driving belt, a belt shifter, belt pulleys, a tension device connected to said shifter, a latch casing, a slotted sliding latch mounted therein for movement relative to said shifter, a cam disposed within the slot of said latch, and a lever arm from said cam connected to said guard member.
16. In a stopping device, a movable guard member, driving belts, a slideable shaft provided with a plurality of holding devices, a belt guide bracket thereon, pulleys co-operating with said belts, means controlled by said guard member for engaging either of said devices upon said shaft, and a tension device connected to said shaft to restore it to initial position.
17. In a stopping device, a movable guard member, driving belts, a slideable shaft provided with a plurality of holding devices, a belt guide bracket thereon, pulleys co-operating with said belts, means controlled by said guard member for engaging either of said devices upon said shaft and restoring weights having flexible connections extending to said shaft.
18. In a stopping device, a movable guard member, driving belts, a slideable shaft provided with a plurality of holding devices,

a belt guide bracket thereon, pulleys coöperating with said belts, means controlled by said guard member for engaging either of said devices upon said shaft restoring 5 weights having flexible connections extending to said shaft, and curved guide tubes through which said flexible connections pass.

19. In a stopping device, a movable guard member, a driving belt, a slideable shaft provided with retaining recesses therein, a belt guide carried by said shaft, pulleys coöperating with said belt, retaining means adapted to enter the recesses of said shaft, a connection from the said means to the guard member and means for automatically shifting said shaft when released from the retaining means.

20. In a stopping device, a movable guard member, a driving belt, a slideable shaft provided with retaining recesses therein, a belt guide carried by said shaft, pulleys coöperating with said guide, retaining means adapted to enter the recesses of said shaft, a connection from the said means to the guard member, means for automatically shifting said shaft when released from the retaining means, a rock shaft, a lever arm extended therefrom and connected to said slideable shaft, and an operating lever carried by said rock shaft.

21. In a stopping device, a pivoted guard member, a rock shaft adapted to be actuated thereby, a driving shaft, parallel loose pulleys and an intermediate tight pulley thereon, driving belts for said pulleys, a slideable belt shifter mounted to coöperate with said belts, independent tension devices connected to said belt shifter to restore it to non-driving position, and a latch mechanism operatively connected to said rock shaft and adapted to retain the shifter in either driving position.

22. In a stopping device, a pivoted guard member, a rock shaft adapted to be actuated thereby, a driving shaft, parallel loose pulleys and an intermediate tight pulley thereon, driving belts for said pulleys, a slideable belt shifter mounted to coöperate with said belts, independent tension devices connected to said belt shifter to restore it to non-driving position, a latch mechanism having an operating lever, a crank lever connected to said operating lever, and a connecting rod from the opposite arm of the belt crank lever 55 to said rock shaft.

23. In a stopping device, a pivoted guard member, a rock shaft adapted to be actuated thereby, a driving shaft parallel loose pulleys and an intermediate tight pulley there-

on, driving belts for said pulleys, a slideable shaft provided with retaining recesses, a plurality of belt guides secured to said shaft, a latch bolt controlled by the guard member and adapted to coöperate with the said recesses, and independent tension devices for 65 restoring said slideable shaft to initial position.

24. In a stopping device, a pivoted guard member, a rock shaft adapted to be actuated thereby, a driving shaft, parallel loose pulleys and an intermediate tight pulley thereon, driving belts for said pulleys, a slideable shaft provided with retaining recesses, a plurality of belt guides secured to said shaft, a latch bolt controlled by the guard member 70 and adapted to coöperate with the said recesses, independent restoring weights, and flexible connections extending in opposite directions therefrom and connected to said slideable shaft.

25. In a stopping device, a pivoted guard member, a rock shaft adapted to be actuated thereby, a driving shaft parallel loose pulleys and an intermediate tight pulley thereon, driving belts for said pulleys, a slideable shaft provided with retaining recesses, a plurality of belt guides secured to said shaft, a latch bolt controlled by the guard member 85 and adapted to coöperate with the said recesses, independent tension devices for restoring said slideable shaft to initial position, a pin extended from said slideable shaft, and a manually controlled shifting lever having a slotted end to embrace said pin.

26. In a stopping device, a movable guard member, a slideable shaft provided with a plurality of retaining recesses having inclined walls upon their adjacent sides, driving belts, driving pulleys, belt guides carried by said shaft, a retaining bolt having a 90 curved face adapted to enter said recesses, and a connection from said bolt to said guard member.

27. The combination with a power controlling device having means under tension 105 for automatically cutting off power, of a pivoted cover screen having its axis operatively connected to release said tension means, a guard board pivoted beneath the free edge of said screen, and connections from said 110 guard board to release said tension means.

In testimony whereof we affix our signatures in presence of two witnesses.

WILLIAM BARTHOLOMEW.

DAVID J. PHILLIPS.
